[57] CLAIM

The ornamental design for a gimble ring light fixture for use on track, as shown and described.

DESCRIPTION

FIG. 1 is a top view of the gimble ring light fixture for use on track showing our new design;

FIG. 2 is a bottom view of the gimble ring light fixture for use on track shown in FIG. 1;

FIG. 3 is a front elevational view of the gimble ring light fixture for use on track shown in FIG. 1;

FIG. 4 is a rear elevational view of the gimble ring light fixture for use on track shown in FIG. 1;

FIG. 5 is a left side elevational view of the gimble ring light fixture for use on track shown in FIG. 1; and,

FIG. 6 is a right side elevational view of the gimble ring light fixture for use on track shown in FIG. 1.

The support and lamp are shown in broken lines for illustrative purposes only.
